UNITED STATES PATENT OFFICE.

DAVID HORSLEY, OF BAYONNE, NEW JERSEY.

PHOTOGRAPHIC-PRINTING MACHINE.

1,059,296.

Specification of Letters Patent. Patented Apr. 15, 1913.

Application filed April 21, 1909. Serial No. 491,249.

To all whom it may concern:

Be it known that I, DAVID HORSLEY, a citizen of the United States, and a resident of Bayonne, in the county of Hudson and State of New Jersey, have invented certain new and useful Improvements in Photographic-Printing Machines, of which the following is a specification.

This invention relates to a photographic printing machine, and its object is the production of such an apparatus in which portions of a film or sensitized paper or other materials are consecutively exposed to light rays during the operation of printing.

In the drawings Figure 1 represents an elevation partly broken away of the invention, Fig. 2 shows a partial section of Fig. 1 on line 2, 2, Fig. 3 is a partial section of Fig. 1 on the line 3, 3, Fig. 4 is a right hand side view partly broken away of Fig. 1, Fig. 5 represents a partial enlarged section of Fig. 2 on the line 5, 5, Fig. 6 shows a partial right hand end view of Fig. 5, Fig. 7 is a section as on the line 7, 7, of Fig. 1 and Figs. 8 and 9 represent the portions of the reel of the invention separated from each other.

A casing is shown at 20 with the front wall 21 having an opening 22, top 23, bottom 24 and hinged side 25. Dovetailed guides 27 on the bottom 24 adjustably support the foot 28 of a support 29 for the lamp 30, which latter in the present case is a Nernst lamp, that is provided with electric current by means of the wires 31. An angle shaped bracket generally designated by the numeral 35 with the members 36 and 37 extends from the front wall 21 of the casing. The foot 38 of the member 36 contains an opening 39 which registers with the opening 22 of the front wall 21. Bosses 44, 45, 46, 47, 48 and the journal bearings 49 and 50 extend from said bracket 35.

In the opening 39 of the foot 38 is supported the tube 53, having a slot with the branches 54 and 55 at right angles to each other. On the tube 53 is telescopically supported the sleeve 56 having fastened to its outer cylindrical surface the ring 57. A pin 59 extends through the ring 57 and sleeve 56 into the slot having the branches 54 and 55.

A spring 60 bears between the ring 57 and the foot 38 of the bracket 35. A segmental cylindrical cap 61 is secured to the outer end of the sleeve 56. A slot 62 and grooves 63 are formed in said cap. A shutter 65 over the opening 22 is fastened to a spindle 66 extending through the front 21 of the casing, and the foot 38 of the said bracket 35. An arm 67 extends from the spindle 66 to operate the shutter, and which is accomplished by moving the said arm 67 and thereby allow the light rays to enter the tube 53.

The journal bearing 49 supports the shaft 70 to which is fastened the sprocket wheel 71 having the sprocket pins 72. A spur gear 65 is fastened to the shaft 70 the teeth of which mesh with the teeth of the pinion 74 fastened to a spindle 75 in the journal bearing 50, and a collar 76 is fastened to the spindle 75 on the other end of the said bearing 50. A pulley 77 fastened to the spindle 75 carries a belt 78, which leads to a pulley 79 of an electric motor 80 mounted on the top 23 of the casing. A pin 85 extends from the boss 47 and on it is pivoted the arm 86, 75 which latter carries the pin 87. An idler roller 88, with the two pair of flange rings 89 extending from its cylindrical surface is journaled on the pin 87. A spring 90 extends from a hook 91 on the arm 86 to a hook 92 on the lower portion of the front wall 21 of the casing. An idler roller 95 with the end flanges 96 is journaled on a pin 97 extending from the boss 46. From the boss 48 extends a pin 101 on which latter is supported a guide plate 98 with the guide edge 99 and guide lugs 100 adjacent to the latter.

A pin 105 extends from the boss 44 on which is journaled a reel 106 for the negative film 107. The said reel comprises the disk 108 which is supported on the sleeve 109 having the inner sleeve 110 connected thereto. A spring clamp 111 with one end fastened to the sleeve 109, encircles the same, 90 and can be used for securing the end of the film 107 to said reel. A tube 112 is slidably supported in the sleeve 109 and carries the accompanying disk 113 of the reel. A screw 114 in the boss 115 can fasten the tube 112 100

to the pin 105, and a screw 116 in the boss 117 can fasten the sleeve 110 to the pin 105.

A pin 118 extends from the boss 45 and carries a reel 120 similar to the reel 106 for the unexposed film 121.

To operate the invention, the negative developed film 107 and the unexposed film 121 having been located on their respective reels 106 and 120 are led against the guide edge 10 99 and lugs 100 of the guide plate 98, with their gelatinized faces adjacent to each other. The films are then lead under the idler roller 95 over the sprocket wheel 71, the openings of both films being engaged by 15 the sprocket wheel to prevent them moving relatively to each other. The grooves 63 in the cap 61 constitute clearance spaces for the pins 72 of the sprocket wheel 71. The idler roller 88 at the same time bears on the 20 films to maintain their faces closely together. To engage the films with the said sprocket wheel 71 the sleeve 56 is moved away from said sprocket wheel so that the pin 59 is engaged by the branch 55 of the 25 slot in the tube 53. After the films are in place the pin 59 is released from said branch 55, and the tension of the spring 60 causes the cap 61 to force the films against the surface of the sprocket wheel 71. The lamp 30 and motor 80 are now operated and the shutter 65 opened. The light rays pass through the tube 53 on their way through the slot 62, to the films and print the unexposed film while it is turning with the negative film 35 over the sprocket wheel 71. Displacements of the films with respect to each other during the operation of printing are thus avoided.

Sensitized photographic paper may be 40 substituted for the unexposed film for printing the copy or positive.

The invention can also be used for making a negative from a developed positive, which may be accomplished by locating the 45 developed film or positive next adjacent to the light rays in the manner described for printing the positives, and then printing said negatives from their accompanying positives. It is also evident that a cylindrical surface or a plane surface might be substituted for the sprocket wheel, and that portions of the printing material, films, paper and the like might be consecutively carried by said surfaces and exposed to the light 50 rays.

Having described my invention what I desire to secure by Letters Patent and claim is:—

1. In a photographic printing machine 60 the combination of a sprocket wheel having a cylindrical surface, means to rotate the sprocket wheel, means to lead a negative film and an unexposed film over the cylindrical surface of said wheel, the pins of

the sprocket wheel simultaneously engaging 65 both of said films, a tube, a sleeve slidably supported on the tube, a segmental cylindrical cap having a slot bearing against the outer surface of the outer film on the cylindrical surface of the sprocket wheel, and 70 means to project light rays through the said tube and said slot to the films during the rotations of the said sprocket wheel.

2. In a photographic printing machine 75 the combination of a sprocket wheel having a cylindrical surface, means to rotate the sprocket wheel, means to lead a negative film and an unexposed film over the cylindrical surface of said wheel, pins of the sprocket wheel simultaneously engaging 80 both of said films, an idler roller adjacent to the cylindrical surface of the sprocket wheel and bearing on the outer film to maintain the accompanying faces of the films together while traveling with the sprocket 85 wheel, a tube, a sleeve slidably supported on the tube, a segmental cylindrical cap on the sleeve having a slot bearing against the outer surface of the outer film on the cylindrical surface of the sprocket wheel, and 90 means for projecting light rays through said tube and said slot to the films during the rotations of the said sprocket wheel.

3. In a photographic printing machine 95 the combination of a casing, a lamp in the casing, a shutter over an opening in the casing in the field of the rays of said lamp, a tube extending from the casing over the opening therein, a sleeve telescopically and rotatably connected to the tube, a spring 100 forcing the sleeve longitudinally on the tube and from the casing, a segmental cylindrical cap for the sleeve provided with an opening, the convex side of the cap being toward the sleeve, a wheel journaled concentrically 105 with the concave face of said cap, and means to simultaneously lead a pair of films between the concave face of said cap and the cylindrical surface of the said wheel.

4. In a picture film printing machine, the 110 combination of a casing, a lamp adjustably secured in the casing, a shutter over an opening in the casing in the field of the light rays of said lamp, a sleeve telescopically connected with the casing, a segmental cylindrical cap having a slot and connected to the sleeve, a bracket extending from the casing, a reel for a negative film journaled on a pin extending from the bracket, a second reel for an unexposed film journaled 115 on a second pin extending from the bracket, a spindle journaled in the bracket, means to rotate the spindle, a pinion fastened to the spindle, a shaft journaled in the bracket, a spur gear on the shaft with its teeth meshing with the teeth of said pinion, a sprocket wheel on the shaft adjacent to said cap, an idler wheel journaled on a pin extending 120

from said bracket, a guide plate for the
films between the said idler wheel and the
said reels, an adjustable arm pivoted on the
bracket, an idler roller pivoted to said arm
5 to maintain the films against the cylindri-
cal surface of the sprocket wheel.

Signed at Bayonne in the county of Hud-

son and State of New Jersey this 13th day
of April A. D. 1909.
